UNITED STATES PATENT OFFICE.

FRANK M. PECK, OF MILLIS, MASSACHUSETTS, ASSIGNOR TO UNITED SHOE MACHINERY COMPANY, OF PATERSON, NEW JERSEY, A CORPORATION OF NEW JERSEY.

PRESSER-FOOT MECHANISM.

1,206,904.

Specification of Letters Patent.

Patented Dec. 5, 1916.

Application filed October 15, 1915. Serial No. 56,150.

To all whom it may concern:

Be it known that I, FRANK M. PECK, a citizen of the United States, residing at Millis, in the county of Norfolk and State of Massachusetts, have invented certain new and useful Improvements in Presser-Foot Mechanism; and I do hereby declare the following to be a full, clear, and exact description of the invention such as will enable others skilled in the art to which it appertains to make and use the same.

The present invention relates to shoe sewing machines and more particularly to presser foot mechanism employed in connection with such machines.

The object of the present invention is to provide certain new and useful improvements in connection with presser foot locking mechanism for sewing machines.

With this object in view the several features of the invention consist in certain novel features of construction, combinations and arrangements of parts hereinafter described and claimed, the advantages of which will be obvious to those skilled in the art from the following description.

In the accompanying drawings illustrating the preferred form of the invention; Figure 1 represents a side elevation of a sewing machine embodying the invention; Fig. 2 is a detail illustrating a plan view of the mechanism for locking the presser foot controlling bar; Fig. 3 is a detail showing a view similar to Fig. 1 partly in section; and Fig. 4 is a cross sectional view taken upon the line 4-4 of Fig. 2.

The machine shown in the illustrated embodiment of the invention is substantially the same as that disclosed in the application of Ashworth, Ser. No. 769,566, filed May 24, 1913. This machine comprises a work support 1 and a coöperating presser foot 2 which is mounted upon one end of a presser foot lever 4 fulcrumed at 5. The presser foot is actuated during the operation of the machine to first engage yieldingly with the work and then positively move a predetermined distance to clamp the work during the formation of a stitch, and is finally elevated and retained in this position during the feed movement of the work after which the cycle of operations is repeated. In order to actuate the presser foot in this manner

the lower end of the presser foot lever is connected through a link 7 with an actuating lever 8 pivoted between its ends to a controlling bar 9 which is locked at predetermined intervals in a block or head 10 through a locking device indicated generally at 11, to be hereinafter described. The lower end of the actuating lever 8 is connected through a link 12 with a tension spring 13 which normally tends to swing the presser foot lever in a direction to move the presser foot into engagement with the work. The upper end of the actuating lever 8 is connected to the lower end of the usual operating lever 15 through a link 16. The actuating lever is fulcrumed at 14 and has its opposite end operatively connected with a rotary cam disk indicated at 17. At the completion of the feeding movement when the work is to be clamped in position by the presser foot the controlling bar 9 is free to move, and the spring 13 accordingly swings the actuating lever 8 about the connection with the link 16 to move the presser foot into yielding engagement with the work. The controlling bar is then locked in position and a cam disk 17 operates through the lever 15 to swing the actuating lever about the connection with the bar 9 to impart a positive movement of predetermined extent to the presser foot.

It is desirable to provide a simple and compact mechanism for locking the bar 9 relative to the block 10 at predetermined intervals and to release the bar to permit its free movement relative to the block 10. It will be noted from an inspection of the drawings that the bar 9 is received in a longitudinal bore formed in the head 10 and is engaged by a clamping jaw supported upon the head. The clamping jaw is conveniently actuated by a sliding plate which is provided with a cam slot engaging with the jaw, and means for reciprocating the plate during each cycle of operations of the machine. To this end the clamping jaw 18 is pivoted at its lower end upon a stud 20 secured in the block 10. The clamping jaw is seated in a transverse recess formed in the block and intersecting the bore in which the bar 9 slides in order that the face of the clamping jaw may engage at intervals with the controlling bar to clamp the bar relative

2 to the block 10. The upper end of the clamping jaw is engaged by a sliding plate 21 provided with a cam slot 23 which receives an upstanding projection 24 formed upon the jaw, as shown clearly in Figs. 2 and 4. The sliding plate is supported upon the block 10 and is guided relative to the block by a guide member 25 projecting upwardly from the block and received in a straight slot 26 formed in the plate.

10 In order to retain the plate in operative relation to the clamping jaw the projection 24 is provided with a flanged head which extends beyond the sides of the cam slot 23. With this construction it will be obvious that a rectilinear movement of the sliding plate swings the clamping jaw about the lower end to engage or disengage the controlling bar 9.

20 In order to insure the positive locking of the controlling bar relative to the block 10 the bar is conveniently provided with a threaded portion 27 of suitable length which is engaged by similarly shaped teeth 28 formed upon the coöperating face of the clamping jaw. The movements of the sliding plate are controlled in the usual manner through a curved lever 30 fulcrumed upon a shaft 31 and directly connected at one end 30 to the sliding plate 21. The lever 30 is normally maintained in position to lock the controlling bar through a spring 35 connected with the opposite end of the lever 30 and is unlocked at predetermined intervals 35 by an arm 36 fulcrumed upon the shaft 31 and connected to the lever 30 through the usual type of lost motion connection.

40 While it is preferred to employ the specific construction and arrangement of parts shown and described, it will be understood that this construction and arrangement is not essential except so far as specified in the claims, and may be changed or modified without departing from the broader features 45 of the invention.

The invention having been described, what is claimed is;

1. A presser foot mechanism for sewing machines, having in combination, a presser foot, a controlling bar connected with the 50 presser foot, a block through which the bar passes, a clamping jaw supported upon the block, a sliding plate provided with a cam slot engaging the jaw, and means for reciprocating the plate during each cycle of operations of the machine to actuate the clamping jaw.

2. A presser foot mechanism for sewing machines, having in combination, a presser foot, a controlling bar connected with the 60 presser foot, a block through which the bar passes, a clamping jaw pivoted upon the block, a sliding plate for moving the clamping jaw toward and from the controlling bar, and means for reciprocating the plate 65 during each cycle of operations of the machine.

3. A presser foot mechanism for sewing machines, having in combination, a presser foot, a controlling bar connected with the 70 presser foot, a block through which the bar passes, a clamping jaw supported upon the block, a sliding plate provided with a cam slot engaging the jaw, connections between the block and plate for guiding the plate in 75 a rectilinear path, and means for reciprocating the plate during each cycle of operations of the machine.

4. A presser foot mechanism for sewing machines, having in combination, a presser 80 foot, a threaded controlling bar connected with the presser foot, a block through which the bar passes, a clamping jaw pivoted upon the block and having a toothed surface arranged to engage with the threaded portion 85 of the bar, and mechanism for moving the clamping jaw toward and from the bar during each cycle of operations of the machine.

FRANK M. PECK.
